UNITED STATES PATENT OFFICE.

MICHAEL SEIDNER, OF BUDAPEST, HUNGARY.

LIQUID-COOLED ELECTRIC MACHINE.

Application filed March 18, 1919. Serial No. 283,442.

To all whom it may concern:

Be it known that I, MICHAEL SEIDNER, a citizen of Hungary, residing at 5 Zsigmond utca, Budapest, Hungary, have invented 5 certain new and useful Improvements in Liquid-Cooled Electric Machines (for which I have filed applications in Germany December 29, 1917, Patent No. 337,561; in Hungary, April 17, 1919, application Number 10 S. 9495; and in Switzerland September 4, 1919, application Number 1375), of which the following is a specification.

My invention relates to new and useful improvements in liquid-cooled electric machines.

The primary object of my invention is to eliminate the disturbing effect of the rotor or rotating member caused on the one hand by the centrifugal force, and on the other 20 hand by the relative motion between the rotor or rotating member and the stator or stationary member.

Another object of my invention is to provide means which will make liquid-cooling 25 possible for both members of high-speed electric machines, or for the outer member of such machines, hitherto it being only possible to cool the armature of such machines by means of liquid by fitting the 30 whole armature with a liquid-tight enclosure.

A further important object of the invention resides in the provision of a very efficacious direct cooling of the conductors or 35 windings by conducting the cooling liquid along the conductors or windings in immediate contact with the same.

With these objects in view, the invention 40 consists of certain new combinations and arrangements of parts which will enable each of the two members of the machine to carry its own cooling liquid individually so that the liquid cooling the one member cannot 45 strike on the other member, as hereinafter fully described and claimed, and illustrated in the accompanying drawings, in which:—

Fig. 1 is a vertical axial or longitudinal section of a turbogenerator embodying my invention. Fig. 2 is a vertical axial or longitudinal section of a turbogenerator showing 50 a modified form of my invention. Figs. 3, 4, 5, 6 and 7 are detail sectional views showing how the cooling liquid may be led within the insulations of the windings or conductors in immediate contact with the latter. Fig. 8 indicates how the iron core may be

provided with axial borings for the passage of the cooling liquid, and with slots for the reception of the windings. Fig. 9 is a vertical longitudinal or axial section of a 60 solid rotor-body showing a preferred embodiment of the invention. Fig. 10 is a vertical transversal section of the same rotor-body. Figs. 11 and 12 show details in a larger scale to illustrate the arrangement 65 of directly cooled windings in the slots of a laminated stationary member within pipes preventing the escape of the liquid between the laminations.

Similar reference numbers refer to similar parts throughout the several figures.

I am aware that, in the early art of the manufacture of electric machines, it has been proposed to pass cooling liquid through the solid cores of both the stationary and 75 the rotating member. I am also aware of propositions having been made to cool the back or the end surfaces of the stationary magnet-core by a liquid medium. My present invention is, however, entirely differentiated 80 from these known constructions which provide a mere local cooling of a few parts easily accessible to the liquid medium, in that my invention relates to the substitution of the entire ventilating arrangement 85 particular especially with large dynamo electric machines and affecting also the conductors or windings embedded in the iron cores. To provide such thorough liquid-cooling as by air-ventilation of all parts, 90 and especially the predominant heat-sources, of an electric machine was not, hitherto, possible but for the inner member of the machine, whereas the present invention affords means 95 both members to be cooled by means of liquid in the same way as by air-ventilation.

Referring now to Fig. 1, the usual side shields 1 and 2 of the stationary member, one on each side of the machine, are connected by a tube 3 tightly fastened on the inner periphery of said shields and passing through the air-gap between rotor and stator. A second tube 4 within the former is fitted as a mantle over the rotor, forming with disks 7 and 8 fitting over the shaft parts 5 and 6, a liquid-tight enclosure for the whole rotor. In this way, the rotating as well as the stationary member each are formed as an individual tightly closed 110 casing which is filled with the liquid cooling medium.

The liquid-filled inner space of the stator casing or shell is divided by partitions 61 arranged in alinement with the end disks 11, 12 and protruding inwardly from the outer mantle 62 of the casing or shell, into the annular chambers 22, 51 and 23. The bottom of the front chamber 22 is provided with an inlet 49 to supply fresh cooling liquid, and the top of the middle chamber 51 is provided with an outlet 52 for the escape of the heated medium. In the partition between the middle chamber 51 and the back chamber 23, a passage 50 is formed at the bottom.

15 Inlet and outlet passages for the rotating member are created by axial borings 53 and 56 of the spindles 5 and 6, respectively, each axial boring communicating through radial borings 54, 55 with the end chambers 24, 25 20 of the rotor-shell.

The coil heads or ends 18 and 19 of the stator as well as those 20 and 21 of the rotor being placed in the spaces 22, 23 and 24, 25, respectively, filled with cooling liquid, 25 they are cooled in a very effective manner. For the purpose of cooling the iron cores 13 and 26, these are formed with axial notches 27, 28, 29, borings 30, longitudinal holes 31 etc. (Fig. 8), or with gaps 33 (Fig. 30 1) running perpendicularly to the shaft, through which the cooling medium is led from the one liquid-filled space to the other.

In order to let the cooling liquid come into direct contact with the windings 34 35 and 35, the latter are arranged in the slots 36 and 37 of the iron cores so as to allow the free passage of the cooling liquid. Such passage may be afforded by suitable 40 grooves 27, 28 in the slots 38 (Fig. 8), slots or openings 39, 40 in the conductor material itself (Figs. 3 and 4), pipes 41 inserted between the conductors within the insulation (Fig. 6), interstices 42, 43 and 44 between the several conductors placed 45 within the slot insulation (Figs. 5, 7, and 12).

Machines with an air-gap not wide enough for the reception of the two tubes 3 and 4, or in which the diameter of the rotating member would become too large on account of the very high circumferential speed, may have, instead of a sole tube for the rotor and stator extending over the whole length of the machine, two such tubes 55 extending only over the coil heads. Such arrangement is shown in Fig. 2; the inner edges of the tubes 9 and 10, which are used instead of the sole tube 3 (Fig. 1), are tightly fitted to the end disks 11 and 12 of 60 the stator body 13.

The rotor ends may be closed in the same manner by tubes fitted on the one hand to the disks 7 and 8 (Fig. 1) and on the other hand to the end disks 14 and 15 of the rotor-body, or, as illustrated in Fig. 2, by hood-

like shields 16 and 17. It is understood that the tubes 9 and 10 may be made with the end shields 1 and 2, respectively, of one solid piece. The various forms just described may also be combined for the stationary and rotating member as desired. 70

In order to allow the cooling liquid to be led from the one space 24 into the other 25 without escaping between the laminations or through the open slots, when only end shields are used, I furnish the axial slots or openings of the iron core with a lining of pipes 45, 46, 47, 48 connecting the end spaces of liquid with one another and tightly fitted into the end disks 14 and 15. 80 The latter have, for this purpose, closed slots, even though the iron cores have open slots. In Figs. 11 and 12, this arrangement can be seen on a larger scale in connection with the stationary member. The pipes 46, 48 are made of metal, or, if necessary, of some suitable insulating material. All variations represented by Figs. 3 to 7 may be used with this arrangement. 85

The course of the cooling medium 90 through the machine is the following. In the stator: inlet 49, space 22, axial openings of the laminations, space 23, passage 50, space 51, gaps 33, outlet 52. In the rotor: shaft borings 53 and 54, space 24, axial slots and openings of the iron body, space 25, shaft borings 55 and 56. The liquid leaving the machine is led into a cooling apparatus before being used again.

In Figs. 9 and 10, I have shown a solid 100 rotating member of a turbogenerator having its end spaces for the cooling liquid closed by the shaft-flanges 57, 58. Besides, the slots 60 for the windings 59 are constructed as closed borings of the iron body which, if 105 interstices are provided between the several conductors or between these and the slot walls, may be used without more ado as passages for the liquid cooling medium so that the insertion of particular pipes, as in Figs. 11 and 12, becomes superfluous. 110

It is understood that, instead of an integral casing, each of the two members of the machine may be furnished with two or more 115 separate casings or shells without departing from the spirit of the invention. Moreover, although I have shown the casings containing the cooling liquid so as to embrace the whole stationary or rotating member, I do not wish to be limited to this simple and preferred embodiment of the invention, but the liquid-filled casing or several casings may, if desired, embrace only such particular parts of the one or other member, always inclusive of the pertinent windings, as require 120 a more intensive cooling.

Having thus described my invention, what I claim and desire to secure by Letters Patent is—

1. In a liquid-cooled electric machine con- 130

sisting of a rotatable and a stationary member both with windings, means to form liquid-tight inclosures for each member individually embracing also the windings, a liquid cooling medium in said inclosures, each member having its own sealing walls for its liquid-containing spaces in front of the other member so as to prohibit the liquid medium cooling the one member from coming into contact with the inclosure or any part of the other member.

2. In a liquid-cooled electric machine consisting of a rotor and a stator both with windings, the combination of a non-laminated rotor formed as a shell, and adapted to have cooling liquid passed therethrough in proximity to the windings to carry off the heat produced by the current in the latter, with stationary means to form a liquid-tight 20 inclosure embracing the stator together with its windings, said stator having its own sealing walls for its liquid-containing spaces in front of the adjacent periphery of the rotor so as to prohibit the liquid cooling 25 the stator from coming into contact with the rotor.

3. In a turbogenerator, the combination of

a solid rotor-core carrying its windings in closed longitudinal ducts, flanged shafts attached to said rotor-core at both ends thereof, their flanges covering the end-connections of the windings, shaft-ducts forming inlet and outlet passages for a liquid cooling medium, recesses on the inner surface of the flanges for the reception and distribution of the cooling liquid in contact with the end-connections of the winding which only partly fill said longitudinal ducts of the rotor-core to establish communication for the cooling liquid between said recesses, with stationary means to form a liquid-tight inclosure embracing the stator together with its windings and having its own peripheral walls in front of the adjacent periphery of the rotor so as to prohibit the liquid cooling 45 the stator from coming into contact with the rotor.

In testimony whereof I affix my signature in presence of two witnesses.

MICHAEL SEIDNER.
